UNITED STATES PATENT OFFICE

2,453,879

LOCKING MEANS FOR ADJUSTABLE BACK CHAIRS

Tracy H. Van Buren, Sturgis, Mich.

Application November 9, 1946, Serial No. 708,893

9 Claims. (Cl. 155—157)

1

This invention relates to improvements in adjustable chairs.

The main objects of this invention are:

First, to provide an adjustable chair having a wide range of adjustment and which may be quickly and easily adjusted to the particular requirements or comfort of the user.

Second, to provide in a chair means for adjustably supporting the back which is very secure and does not depend on screws or clamping adjusting means.

Third, to provide a back supporting and adjusting means for chairs embodying coacting clutch members which may be easily engaged and disengaged and one in which the strains and stresses thereon are well distributed.

Objects relating to details and economies of the invention will appear from the description to follow. The invention is defined and pointed out in the claims.

A preferred embodiment of the invention is illustrated in the accompanying drawing, in which:

Fig. 1 is a side elevation of a chair embodying my invention.

Fig. 2 is an enlarged fragmentary view mainly in section on a line corresponding to line 2—2 of Fig. 4.

Fig. 3 is an enlarged fragmentary view mainly in section on line 3—3 of Fig. 2.

Fig. 4 is a view mainly in transverse section on line 4—4 of Figs. 2 and 3.

Fig. 5 is an elevational view of one of the cam elements.

Fig. 6 is a fragmentary elevational view of the other cam element.

The embodiment of the invention illustrated is an office chair comprising a pedestal 1, a seat 2 provided with the vertically adjustable spindle 3. The back of the structure illustrated comprises a supporting bar 4 carrying the pad-like back member 5 which is tiltably mounted on the pivot 6. The details however of this mounting form no part of my present invention and are therefore not illustrated.

The back supporting arm 7 is disposed below the seat and projects rearwardly from the spindle 3. This arm is provided with a segmental curved serrated jaw 8 at its rear end. The back bar 4 is engaged in the socket 9 of the back supporting bracket 10. This back supporting bracket is provided with a curved segmental serrated jaw 11 at its forward end. The serrations or the teeth of these jaws are laterally inclined in the same direction.

2

The supporting link designated generally by the numeral 12 comprises a pair of link members 13 and 14 which are conformed to provide a central chamber 15. The link members are secured together and pivotally connected to the arm 7 and bracket 10 by rivets 16. These combination rivets and pivots are centered relative to the jaws 8 and 11.

The intermediate or adjusting clutch member 17 is provided with segmental concaved serrated or toothed jaws 18 at its ends, the serrations or teeth being inclined laterally and oppositely to the serrations or teeth of the jaws 8 and 11. The adjusting clutch member 17 is supported for lateral sliding adjustment by means of the ways 19 provided on the link 12 for the purpose.

The adjusting clutch member 17 is adjusted into and out of engagement by means of the spindle 20 rotatably mounted in the supporting link 12 and provided with a hand piece 21 at one end, the hand piece being secured thereto by the pin 22.

The spindle is shouldered at 23 to engage one side of the clutch member 17 and is provided with a pin 24 engaging the other side, this connection permitting rotative movement of the spindle within the adjusting clutch member. The spindle is provided with means for moving it axially when it is rotated. In the embodiment illustrated this comprises the cam element 25 which is formed at the bottom of the recess 26 in the link member 14 and a coacting cam element 27 formed on the inner face of the closure member 28 for the recess.

This closure member 28 has an annular groove 29 on its inner side receiving the annular flange 30 on the link member 14 to which it is secured by the screws 31. These cam elements in effect provide a cam groove with which the pin 32 on the spindle coacts so that when the spindle is rotated an axial movement is imparted thereto and inasmuch as the adjusting clutch member is connected to the spindle for axial movement therewith the clutch jaws are moved into and out of engagement.

When the parts are in engaged position they are very securely locked in adjusted position and stress on the jaw members is well distributed. The parts are capable of a very wide range of adjustment and are securely locked in adjusted positions.

I am aware that adjustable parts for backs have been provided in which screws are relied upon to clamp the clutch members together such, for example, as are shown in the Huntley Patent

1,796,949, issued March 17, 1931. The structure of my invention, however, has many advantages not present in or incident to the structure of the said patent both from the manufacturing standpoint, ease and security of adjustment and in the distribution or strain on the parts.

I have illustrated and described my invention as embodied in an office chair. I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent is:

1. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, the serrations of said jaws being transversely inclined in the same direction, a supporting link comprising a pair of opposed members disposed on opposite sides of said arm and bracket, said link members being connected to each other and pivotally connected to said arm and bracket by fastener members centered relative to the said jaws, an adjusting clutch member having concaved segmental serrated jaws at the ends thereof coacting with the clutch jaws of said arm and bracket, the serrations of said adjusting clutch member jaws being transversely inclined oppositely to the serrations of said jaws of said arm and bracket, a spindle rotatably mounted on said link between said arm and bracket jaws and provided with a hand piece, said spindle rotatably engaging said adjusting clutch member and having a shoulder engaging one side thereof and a pin engaging the other, one of said link members being provided with an outwardly facing recess having a cam at the bottom thereof, and a closure for said recess provided with a cam opposed to said first named cam and coacting therewith to provide a cam groove, said spindle having a pin engaging said cam groove whereby rotative movement of the spindle imparts axial movement thereto to engage and disengage said adjusting clutch member, one of said link members being provided with ways slidably supporting said adjusting clutch member.

2. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, a supporting link comprising a pair of opposed members disposed on opposite sides of said arm and bracket, said link members being connected to each other and pivotally connected to said arm and bracket by fastener members centered relative to the said jaws, an adjusting clutch member having concaved segmental jaws at the ends thereof coacting with the clutch jaws of said arm and bracket, a spindle rotatably mounted on said link between said arm and bracket jaws and provided with a hand piece, said spindle rotatably engaging said adjusting clutch member and having a shoulder engaging one side thereof and a pin engaging the other, one of said link members being provided with an outwardly facing recess having a cam at the

bottom thereof, and a closure for said recess provided with a cam opposed to said first named cam and coacting therewith to provide a cam groove, said spindle having a pin engaging said cam groove whereby rotative movement of the spindle imparts axial movement thereto to engage and disengage said adjusting clutch member.

3. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, the serrations of said jaws being transversely inclined in the same direction, a supporting link comprising a pair of opposed members disposed on opposite sides of said arm and bracket, said link members being connected to each other and pivotally connected to said arm and bracket by fastener members centered relative to the said jaws, an adjusting clutch member slidably mounted on said link and having concaved segmental serrated jaws at the ends thereof coacting with the clutch jaws of said arm and bracket, the serrations of said adjusting clutch member jaws being transversely inclined oppositely to the serrations of said jaws of said arm and bracket, and a spindle rotatably mounted on said link between said arm and bracket jaws, said link being provided with cam means with which said spindle coacts to impart axial movement to the spindle when the spindle is rotated, said spindle being operatively connected to the adjusting clutch member so that the adjusting clutch member is engaged and disengaged by a rotative movement of the spindle.

4. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, a supporting link comprising a pair of opposed members disposed on opposite sides of said arm and bracket, said link members being connected to each other and pivotally connected to said arm and bracket by fastener members centered relative to the said jaws, an adjusting clutch member slidably mounted on said link and having serrated jaws at the ends thereof coacting with the clutch jaws of said arm and bracket, and a spindle rotatably mounted on said link between said arm and bracket jaws, said link being provided with cam means with which said spindle coacts to impart axial movement to the spindle when the spindle is rotated, said spindle being operatively connected to the adjusting clutch member so that the adjusting clutch member is engaged and disengaged by a rotative movement of the spindle.

5. In a chair, the combination with a seat and back, of a back supporting arm disposed below the seat and provided with a segmental serrated clutch jaw, a back supporting bracket provided with a segmental serrated clutch jaw, the serrations of said jaws being transversely inclined in the same direction, a supporting link pivotally connected to said arm and bracket, the pivots being centered relative to the jaws thereof, a coacting clutch adjusting member provided with serrated clutch jaws operatively associated with the clutch jaws of said arm and bracket and transversely inclined oppositely to the jaws of said arm and bracket, means for engaging and

disengaging said coupling clutch member comprising a spindle rotatably mounted on said link and having cam means associated therewith whereby the spindle is moved axially by a rotative movement thereof, said adjusting clutch member being connected to said spindle for movement axially therewith.

6. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, the serrations of said jaws being transversely inclined in the same direction, a supporting link comprising a pair of opposed members disposed on opposite sides of said arm and bracket, said link members being connected to each other and pivotally connected to said arm and bracket by fastener members centered relative to the said jaws, an intermediate clutch member slidably mounted on said link and having concaved segmental jaws at the ends thereof coacting with the clutch jaws of said arm and bracket, the serrations of said adjusting clutch member jaws being transversely inclined oppositely to the serrations of said jaws of said arm and bracket, and means for laterally adjusting said intermediate clutch member.

7. In a chair, the combination with a seat and a back supporting bar, of a back supporting arm disposed below the seat and provided with a segmental serrated clutch jaw at its outer end, a supporting bracket for said back bar provided with a segmental serrated clutch jaw at its front end, a supporting link comprising a pair of opposed members disposed on opposite sides of said arm and bracket, said link members being connected to each other and pivotally connected to said arm and bracket by fastener members centered relative to the said jaws, an intermediate clutch member slidably mounted on said link and having serrated jaws at the ends thereof coacting with the clutch jaws of said arm and bracket, and means for laterally adjusting said intermediate clutch member.

8. In a chair, the combination with a seat and back, of a rearwardly projecting back supporting arm provided with a curved toothed clutch jaw, a back supporting bracket provided with a curved toothed clutch jaw, a supporting link pivotally connected to said arm and bracket with the pivots centered relative to said jaws, a coacting adjusting clutch member provided with curved toothed clutch jaws operatively associated with the clutch jaws of said arm and bracket to be engaged with and disengaged therefrom by a lateral movement thereof, the teeth of the coacting jaws being laterally inclined to facilitate engagement thereof, and means for shifting said adjusting clutch member into and out of engaging position comprising a spindle rotatably mounted on said link and having cam means associated therewith whereby the spindle is moved axially by a rotative movement, said adjusting member being connected to said spindle for movement axially therewith.

9. In a chair, the combination with a seat and back, of a rearwardly projecting back supporting arm provided with a curved toothed clutch jaw, a back supporting bracket provided with a curved toothed clutch jaw, a supporting link pivotally connected to said arm and bracket with the pivots centered relative to said jaws, a coacting adjusting clutch member provided with curved toothed clutch jaws operatively associated with the clutch jaws of said arm and bracket to be engaged with and disengaged therefrom by a lateral movement thereof, and means for shifting said adjusting clutch member into and out of engaging position.
